GOLF PUTTER

Raymond O. McAllister, 3901 SE. 8th St.,
Oklahoma City, Okla. 73115

Filed Mar. 24, 1967, Ser. No. 6,377

Term of patent 14 years

Int. Cl. D21—03

U.S. Cl. D34—5

FIG. 1 FIG. 2 FIG. 3 FIG. 4

FIG. 5 FIG. 6

FIGURE 1 is a front elevational view of a golf putter showing my new design;

FIGURE 2 is a side elevational view of the golf putter viewed 90 degrees from the view in FIGURE 1;

FIGURE 3 is a side elevational view of the golf putter from the side opposite that shown in FIGURE 2;

FIGURE 4 is a rear elevational view of the golf putter;

FIGURE 5 is a top plan view of the golf putter shown in FIGURE 1; and

FIGURE 6 is a bottom plan view of the golf putter shown in FIGURE 1.

I claim:

The ornamental design for a golf putter, substantially as shown.
